UNITED STATES PATENT OFFICE.

JOHN PETER WEIS, OF NYACK, NEW YORK, ASSIGNOR OF ONE-HALF TO METROPOLITAN SEWING MACHINE CORPORATION, OF DOVER, DELAWARE, A CORPORATION OF DELAWARE.

METHOD OF SIMULTANEOUSLY CUTTING AND SEWING SHIRTS AND THE LIKE.

1,342,009.

Specification of Letters Patent.

Patented June 1, 1920.

Application filed January 2, 1919, Serial No. 269,278. Renewed December 24, 1919. Serial No. 347,192.

To all whom it may concern:

Be it known that I, JOHN PETER WEIS, a citizen of the United States, residing at Nyack, in the county of Rockland and State of New York, have invented certain new and useful Improvements in Methods of Simultaneously Cutting and Sewing Shirts and the like, of which the following is a specification.

10 This invention comprises the herein-described method of simultaneously cutting and sewing the shoulder-forming seams and of separating integral, successive, shirt-forming sections from a flattened tube of 15 tubular knit goods.

The objects of the invention are to facilitate high speed and accurate and economical formation of the shoulder seams with reference to the neck openings and in such 20 a way as to eliminate the present hand trimming of the neck openings; and to produce in a flattened tube a succession of shirt-forming integral shoulder-seamed portions that may be transversely severed one from 25 another by a subsequent cutting operation.

In the accompanying drawing forming part hereof, I show flattened tubular goods 30 spreader members 2 at each end of which the tube is held between a spreader and a spreader supporting roll 3 and a rearward pair of feed rolls 4. Forwardly of and between the spreader and the feed rolls 4, the flattened tube portion 5 is of normal width, but the spreader acts to stretch the flattened 35 tube across its width as well as to hold the two walls of the flattened tube spaced flatwise apart; and the rearward rolls in co-operation with the spreader keep the widened portion 6 of the tubular goods between the 40 spreader and the feed rolls under lengthwise tension. In this condition, two parallel lines of stitching are formed at right-angles to the line or path of feed or of the goods in each margin thereof, both lines of stitching 45 on each margin extending only part way toward the neck opening area which is midway between the four seams. These four seams are severally indicated by 7 in dotted lines which at 8, 8 show the original folded 50 edges of the flattened tube, and opposed transverse marginal cuts along the line 9 through the opposed walls and edge of the flattened tubular goods, at each side of the flattened tube, permit a gaping action of the

material so that inwardly of each folded edge of the flattened and marginally cut tube the cut and seamed margins yawn apart forming opposed V-shaped spaces 10 as shown; and in machine practice two such marginal cuts are made simultaneously by 60 cutters, one at one side and the other at the other side of the flattened tubular goods; each cutter working in conjunction with two pairs of stitch-forming devices, there being one pair of such devices for each margin of the cut at each side. The cutting and simultaneous sewing are preferably begun at the inward ends of the cuts and when the cutting and stitch-forming devices operating on each side of the flattened tubular goods, 65 leave the goods, the opposite edges of the sides of each V-shaped space 10 are adjacently severally seamed along the lines 9, forming two opposed shoulder seams transversely of each margin of the flattened tube. 70 The portion of the goods between the spreader and feed rolls comprises the upper portions of two integral shirt-forming portions of the goods.

In practice the armholes 11 and the front 80 openings 12 are formed in the progress of the goods through the machine. The apices of the V-shaped spaces 10 opposingly terminate at each side of a portion of the goods indicated by the circular dotted line 12^a, 85 where the goods are subsequently cut out to form neck openings; but in the immediate operation as the goods travel through the machine, the goods are completely severed along the line 9—9, between the points 9^a, 9^a 90 shown in the dotted circle, whereby two shirts are produced for finishing operations. The first two cuts are marginal cuts to allow the goods to yawn to produce the clearances or V-spaces 10; and the final cut-off or 95 separation of the two shirt bodies is at the line 9—9 when the goods have been advanced to bring that line into the position of the line 13—13 beyond the rear feed rollers 4, the line 13—13 representing the 100 path of the transverse cut off.

What I claim is:

The method of cutting and sewing shirts from tubular goods, consisting in flattening and laterally distending the tube; in putting 105 the flattened and laterally distended tube under lengthwise distension; and while such tube is in its flattened, laterally and length-

wise distended condition, in forming opposed shoulder-forming cuts through the opposite margins of the tube, each cut extending from an edge of the tube part way to the place of the neck opening; and in simultaneously with the making of each marginal cut, forming a seam at each side of each cut; and in thereafter transversely sev-

ering the so-cut and shoulder-seamed portions of the tube along a line intersecting the integral portions of the goods between the inner ends of the two seams on each side of said tube.

In testimony whereof I have hereunto set my hand this 27th day of December, 1918.

JOHN PETER WEIS.
